UNITED STATES PATENT OFFICE.

SAMUEL E. GUINN, OF JOHNSON CITY, TENNESSEE, ASSIGNOR TO S. E. GUINN MANUFACTURING COMPANY, INC., OF JOHNSON CITY, TENNESSEE, A CORPORATION OF NEW YORK.

DESIGN FOR A SMOKER'S STAND.

Application filed March 4, 1926. Serial No. 16,787. Term of patent 14 years.

To all whom it may concern:

Be it known that I, SAMUEL E. GUINN, a citizen of the United States, residing at Johnson City, in the county of Washington and State of Tennessee, have invented a new, original, and ornamental Design for a Smoker's Stand, of which the following is a specification, reference being had to the accompanying drawing, forming part of the application, and in which the figure is a perspective view of the smoker's stand showing my new design.

I claim:

The ornamental design for a smoker's stand, as shown.

SAMUEL E. GUINN.
